UNITED STATES PATENT OFFICE.

DAVID HJORTH, OF BRIDGEPORT, CONNECTICUT, ASSIGNOR TO THE GENERAL MACHINE & MANUFACTURING CO., OF BRIDGEPORT, CONNECTICUT, A CORPORATION OF CONNECTICUT.

ELECTRIC SNAP-SWITCH.

1,379,819.

Specification of Letters Patent. Patented May 31, 1921.

Application filed February 24, 1919. Serial No. 278,600.

To all whom it may concern:

Be it known that I, DAVID HJORTH, a citizen of the United States, and resident of Bridgeport, in the county of Fairfield and State of Connecticut, have invented certain new and useful Improvements in Electric Snap-Switches, of which the following is a specification.

My invention relates to new and useful improvements in electric snap-switches of the rotary type, and wherein is included an operating spindle and a spring to be tensioned to quickly throw the switch-bar from one position to another for making and breaking its contact with the terminals.

The purpose of the invention is to generally improve upon the construction of electric snap-switches of the above class, and especially to provide a simple, cheap and durable switch that may be made of sheet metal parts so as to be quickly stamped from sheets and conveniently assembled; to provide a switch which may be operated to throw the switch-bar from one position to another representing a quarter of a turn, by less than a half turn of the operating button; and further to design the stem with a bearing in both its base and closure cap, and an operating handle upon the outer end whereby the stem may be rotated to operate the switch.

The various further and subsidiary objects and advantages of the invention will more fully appear from the following detailed description and will then be recited in the claims hereto appended.

Similar characters of reference denote like or corresponding parts throughout the several figures of the accompanying drawings forming a part of this specification and upon which—

Figure 1 shows a vertical sectional elevation taken through the central portion of my improved construction of snap-switch.

Fig. 2 is a detached sectional elevation of the operating stem and parts mounted thereon.

Fig. 3 is a bottom end view of the stem and cams carried thereby, and also shown in Fig. 2.

Fig. 4 is a sectional plan view of the switch-bar, operating stem and spring connecting the two, and

Fig. 5 is a plan view of the porcelain base

upon which the several other parts of the switch are mounted.

Referring in detail to the characters of reference marked upon the drawings, 6 represents the base which may be formed of porcelain and is provided with holes 7 in which wires are led for attachment to the binding posts 8 mounted upon the top side of the porcelain. Each of these binding posts are provided with an inwardly disposed blade forming a terminal 9 with which the socket ends of the switch-bar contact. A central hole 10 is formed in the body of the base to receive the lower reduced end 11 of the spindle 12 having an operating handle 13 attached to its upper end. A sheet metal housing 14 is seated upon the porcelain, and provided with a hole through which the stem 12 extends for the purpose of inclosing the operative parts of the switch.

The switch-bar is made up of several parts which form the single operable member, and is loosely mounted upon the stem so that both the switch bar and stem will be susceptible of limited independent rotary movements. The spring 15 which is positioned around the stem has one end secured to the stem at 16 and its other end in engagement with the switch bar as at 17. This forms the operative connection between the two and insures a spring tension upon the switch bar by the turning of the stem.

The switch bar proper consists of an upper sheet metal member 18, a lower similar shaped member 19 and a bottom yoke 20 all of which are secured together by rivets 21, the said members 18 and 19 being spaced apart by washers 22 and through which the rivets also pass. The side edges of the outer socket end portions of the switch bar are turned up slightly to better insure the engagement of the said bar with the terminals when the bar is operating to turn from one position to another. A hub 23 is formed upon the under side of the bottom yoke 20 of the switch-bar that is provided with a peripheral shoulder 24 which in practice is engaged by one of the four pawls 25 pivotally mounted upon the base plate 26, fitted within a recess of the porcelain base. These pawls are normally held in operative engagement with the hub and shoulder by an encircling spring 27 that

engages their upwardly disposed blade portion 28. These pawls engage with the shoulder 24 in their respective order, with the successive operations of the switch, and each 5 pawl serves to engage with the shoulder to hold the switch-bar in a fixed position pending the further turning of the stem and the winding of the spring.

In this connection it will be understood 10 that after the spring has been wound sufficiently to impart a force to the switch bar, the second cam 29 mounted lower down upon the stem and fixed thereto will come forward and disengage the particular pawl which is 15 holding the switch-bar, in a manner to release the stem and to allow it to swing around a quarter turn, when it is again engaged by the next pawl to hold it in alignment with the terminals with which it has 20 become engaged.

Integral with the cam 29 is also formed a ratchet wheel 30 which serves to engage the single spring actuated pawl 31 pivotally mounted upon the base plate in a way to 25 hold the stem and switch-bar against backward turning.

From the foregoing it will be seen that a very simply yet practically and durably formed switch is produced, and wherein an 30 effective tension may be quickly applied to the switch-bar and so that when the same is released a quick throw of the bar is made from one position to another, to quickly make or break the contact.

35 Having thus described my invention, what I claim and desire to secure by Letters Patent, is

1. A rotary snap switch having a base, a rotary operating stem mounted therein, 40 terminal posts, a switch bar rotatably mounted upon the stem to engage and disengage the terminals, a spring yieldably connecting the stem and switch bar, a series of spring pressed pawls carried by the base 45 to temporarily engage and hold the switch bar against rotation, a cam secured to the stem and adapted to force the pawls outwardly to successively disengage them in a manner to allow the switch bar to throw 50 against the next pawl in advance of the movement of said cam.

2. A rotary snap switch having a base, a rotary operating stem mounted therein, terminal posts, a switch bar rotatably mounted 55 upon the stem to engage and disengage the terminals, a spring yieldably connecting the stem and switch bar, a series of spring pressed pawls carried by the base to temporarily engage and hold the switch bar 60 against rotation, a cam secured to the stem and adapted to force the pawls outwardly to successively disengage them in a manner

to allow the switch bar to throw against the next pawl in advance of the movement of said cam, a fixed pawl, and a ratchet secured to the stem to prevent backward turning of the stem and switch bar. 65

3. A rotary snap switch having a base, a rotary operating stem mounted therein, terminal posts, a switch-bar rotatably mounted 70 upon the stem and having a hub portion fitted to turn upon the stem and provided with a peripheral shoulder, a base plate, a series of pawls pivotally mounted upon the plate around the hub to engage its shoulder, 75 a cam secured to the stem to engage the pawls to release the switch-bar, and means to prevent backward turning of the stem and switch-bar.

4. A rotary snap switch having a base, a rotary operating stem mounted therein, terminal posts, a switch-bar rotatably mounted 80 upon the stem and having a hub portion fitted to turn upon the stem and provided with a peripheral shoulder, a base plate, a 85 series of pawls pivotally mounted upon the plate around the hub to engage its shoulder, a single spring encircling the pawls to hold them against the hub and shoulder, a cam secured to the stem to engage the pawls to 90 release the switch-bar, and means to prevent the backward turning of the stem and switch-bar.

5. In a rotary snap switch, a rotatable stem, a rotatable switch bar mounted thereon, 95 said stem and switch bar capable of limited independent rotations, a spring yieldably connecting the stem and switch bar, a series of spring pressed pawls pivotally supported on the base and adapted 100 to engage the switch bar to hold it against rotation, and means for successively forcing the pawls outwardly to allow the switch bar to be actuated with a snap.

6. In rotary snap switch, a rotatable stem, 105 a rotatable switch bar mounted thereon, said stem and switch bar capable of limited independent rotations, a spring yieldably connecting the stem and switch bar, a series of spring actuated pawls pivotally supported on the base and adapted to engage the switch bar to hold it against rotation, 110 and means for successively forcing the pawls outwardly to allow the switch bar to be actuated with a snap, said means comprising a 115 cam secured to said rotatable stem.

Signed at Bridgeport in the county of Fairfield and State of Connecticut this 20 day of February, A. D., 1919.

DAVID HJORTH.
